UNITED STATES PATENT OFFICE.

DORMAN SCHAEFFER, OF HELENA, MONTANA.

DESIGN FOR A TOY VEHICLE.

Application filed July 2, 1926. Serial No. 18,225. Term of patent 14 years.

To all whom it may concern:

Be it known that I, DORMAN SCHAEFFER, a citizen of the United States of America, residing at Helena, in the county of Lewis and Clark and State of Montana, have invented a new, original, and ornamental Design for Toy Vehicles, of which the following is a specification, reference being had to the accompanying drawings, forming a part thereof.

Figure 1 is a side elevation,
Figure 2 is a front elevation, and
Figure 3 is a top plan view showing my new design.

I claim:—
The ornamental design for a toy vehicle as shown.

DORMAN SCHAEFFER.
